ROTARY ABRADING TOOL

Elisha W. Hall, Scituate, and Albin S. Rock, East Bridgewater, Mass., assignors to F. L. & J. C. Codman Company

Application January 12, 1949, Serial No. 70,474

8 Claims. (Cl. 51—193)

1

This invention is concerned with flexible, rotary cylinder, abrading tools of the kind known as tin-plate rollers, and assembled by providing a long, square shaft to which many sections having square openings are applied by pushing them, one at a time, along the shaft under great pressure until the shaft is filled compactly to provide a firm working surface. According to one type of section, the square opening is cut directly in the cotton plies, so that the cotton contacts the shaft. There are several objections attending this type, among which are: (1) lack of stability of the cotton plies, when pressing against a co-operating roller, with consequent tendency of the section to become out-of-round due to the square shape of the hole and to the lack of uniformity of the thickness of the cotton about the shaft, and (2) the difficulty of preventing the sections from retreating as they are pushed along the shaft, one by one, by axial pressure. Both objections are overcome by the construction which is the subject matter of this invention.

The invention will best be understood by reference to the following description when taken in connection with the accompanying drawings illustrative of certain embodiments thereof, while its scope will be pointed out more particularly in the appended claims.

In the drawings:

Fig. 1 is an elevation of a section to be applied to a square shaft to build up a long roller;

Fig. 2 is a sectional view on line 2—2 of Fig. 1;

Fig. 3 is an elevation of a modified section; and

Fig. 4 is a section on line 4—4 of Fig. 3.

Referring to the drawings and to the embodiments of the invention illustrated therein by way of example, and having reference, at first, to Figs. 1 and 2, there is shown an abrading tool comprising a hubless ring 4 of abrading material, such as cotton, composed of many layers secured together as by a circular row of stitches 6, through and through, (see Fig. 2). Usually, the layers are made up by a continuous strip of bias-cut material pieced together at intervals by stitches. Instead of making the section with a square hole to fit the shaft, there is provided a circular hole 7.

To the body of abrading material, as thus constituted, there are secured disks 8 and 10 of material, such as hard fiber, as by adhesive, and having square apertures 12 and 14 to correspond with the square shaft to which the rings are to be applied. The apertures are usually somewhat smaller than the internal diameter of the ring of abrading material. This leaves arc-shaped

voids between the corners of the apertures 12 and 14. The ring, having a circular hole, has a uniform cross-sectional form, so that the ring does not tend to become out-of-round. The square form to fit the shaft is furnished solely by the hard fiber disks 8 and 10 with their square apertures 12 and 14. The fiber disks are sufficiently hard and strong to perform this service, because there are many sections on a shaft, (sometimes 48", and sometimes 72" long). The arc-shaped voids left about the square apertures 12 and 14 do not impair the strength of the ring, in the case of small diameters of sections. In fact, there is something to be gained by having the arc-shaped spaces at intervals so that the unsupported edges of the disks can approach each other under the pressure endwise of the mass of sections, as a hydraulic ram pushes them into place upon the shaft. Thus, the free walls of the disks tend to hug the shaft as the pressure is applied.

This tendency to hug the shaft may be increased by providing means, such as a one-directional clutch, for frictional engagement with the shaft as the ring is moved along the shaft in one direction only, during the application of the ring under pressure, to the shaft. One convenient means, and the one which we prefer to employ, will now be described, referring first to Fig. 2. This may be applied to both disks, if desired, but in this embodiment it is applied to only one disk. The aperture 12, in this case, is much smaller than the shaft to which the section is to be applied, so that its margin will bear against the shaft firmly. To this end, the disk 8 is formed, as in Fig. 1, to produce marginal slopes 16 and slits 18 (see Fig. 1) in the form of a truncated pyramid, or other suitable shape, to cause the margin of the aperture 12 to grip the shaft firmly and to cause the disk 8 to bend somewhat as shown by the dotted lines A, A in Fig. 2. The arrow B shows the direction of the motion of the ring along the shaft. Thus, any backward tendency is resisted, as the pressure of the ram is relieved pending the placing of other rings on the shaft. The margin of the aperture 12 thus creates a ratchet effect along the surface of the shaft owing to the crimping in the square aperture.

In the case of large diameter sections, (see Figs. 3 and 4) much larger than usual, (sometimes as much as 12" or more in diameter) it is sometimes desirable to fill the voids, partially, while leaving some space by providing a filler 20 of some suitable material such as chipboard between two hard fiber disks 22, 22, and spaced

slightly therefrom, as by spaces 24, 24 on opposite sides of the filler 20. While the filler furnishes some reinforcement to the section, in the case of large diameter disks, nevertheless advantage is taken of the presence of voids, so that the disks 22 can bend and hug the surfaces of the shaft. Thus, in this case, the disks are not unsupported between the corners of the square apertures 26 of the disks 22. On the other hand, there is sufficient gripping of the edges of the apertures to furnish the desired holding of a section when the pressure of the ram is released during the application of a second section. However, in this case, also, if further gripping is found desirable, the disks can be provided with marginal slopes like those hereinbefore described in connection with the first form. (See Fig. 2.)

Having thus described these embodiments of the invention, what we claim is:

1. In an abrading tool, the combination of an abrading ring for application to a shaft along with others to form a roller, and means carried by said ring including a disk having an aperture whose margin is formed as a part of a pyramid.

2. In an abrading tool, the combination of an abrading ring for application to a shaft along with others to form a roller, and means carried by said ring including a disk having an aperture whose margin is formed as a part of a pyramid and having slits extending outward from the edges of the aperture.

3. An abrading tool for mounting on a square shaft comprising an annulus of abrading material bounded by outer and inner cylindrical surfaces, the latter being substantially larger than the cross section of the shaft, and a pair of disks of substantial radial stiffness secured to the sides of the annulus to support it concentric with the center line of the shaft, the disks having square openings to fit the shaft, the assembly presenting a clearance inwardly of the disks adjacent said openings to permit inward flexure of the disks into the interior of the annulus.

4. In an abrading tool the combination with an abrading ring for encircling application to a shaft and a disc of radially stiff material overlying a radial face of the ring and having an opening to fit the shaft, the margin of the opening having a laterally deflected portion to bear obliquely on the shaft to yield outwardly therefrom when moved along the shaft in one direction, but which will bend inwardly to jam against the shaft when movement in the opposite direction is attempted.

5. In an abrading tool the combination as defined in claim 4 wherein the disc has a plurality of such deflected portions symmetrically arranged around the shaft to function while the

disc maintains a perpendicular relation to the shaft.

6. In a flexible, rotary abrading tool, the combination of a flexible, open-centered abrading ring to be combined with like rings by axial pressure on and about a non-circular shaft to constitute a roller for tin-plate manufacture, said ring having a circular opening of greater area than the cross section of the shaft, and two disks of substantial radial stiffness affixed to opposite sides of said ring, each disk having an opening to fit the shaft, the disks supporting the ring from the shaft, the space between said disks and within the inner circumference of the ring being empty.

7. In a flexible, rotary abrading tool, the combination of a flexible, open-centered abrading ring to be combined with like rings by axial pressure on and about a non-circular shaft to constitute a roller for tin-plate manufacture, said ring having a circular opening of greater area than the cross section of the shaft, two disks of substantial radial stiffness affixed to opposite sides of said ring and having openings to fit the shaft and a filler between said disks having a central opening to fit the shaft and underlying and supporting the internal circumference of the ring there being a clearance between the lateral sides of the filler and said disk to permit inward flexure of said disk into the space within the ring.

8. An abrading tool for mounting on a square shaft comprising an annulus of abrading material bounded by outer and inner cylindrical surfaces, the latter being substantially larger than the cross section of the shaft, and a pair of disks of substantial radial stiffness secured to the sides of the annulus to support it concentric with the center line of the shaft, the disks having square openings to fit the shaft, the assembly presenting a clearance inwardly of the disks adjacent said openings to permit inward flexure of the disks into the interior of the annulus, at least one margin of at least one portion of the disks being bent laterally to provide a portion which may bend further outwardly when slid over the shaft in one direction, but is bent inwardly to jam against the shaft when movement in the opposite direction is attempted.
